UNITED STATES PATENT OFFICE.

CARL E. CHRISTOPHEL, OF PEARL RIVER, NEW YORK, ASSIGNOR TO DEXTER FOLDER COMPANY, OF PEARL RIVER, NEW YORK, A CORPORATION OF NEW YORK.

AUTOMATIC THROW-OUT MECHANISM FOR PRINTING PRESSES AND THE LIKE.

Application filed May 9, 1923. Serial No. 637,826.

It is common in the art to provide printing presses with automatic throw-out mechanism controlled by sheet actuated tripping devices so arranged that the press and automatic feeder connected therewith will be automatically thrown out when a sheet fails to reach registered position at the front gauges of the press. One form of such mechanism is illustrated in U. S. Patent No. 1,143,630 dated June 22nd, 1915.

The present invention comprises broadly in providing some form of throw-out mechanism for machines designed to operate upon sheets in combination with a controlling detector operated by the side registering movement of a sheet. The improved mechanism is preferably, though not necessarily, employed in combination with a controlling mechanism actuated by the front registry of the sheet, so that the press or other machine will be automatically thrown out in cases where the sheet fails to reach registered position either sidewise or at the front gauges.

In order that the invention may be fully understood it will first be described with reference to the accompanying drawings and afterwards pointed out more particularly in the annexed claims.

In said drawings:

Figure 1 is a side elevation of parts of a printing press and automatic feeder illustrating the improved throw-out mechanism.

Figures 2 and 2^a illustrate together a perspective view of the delivery end of the conveyor looking down and toward the rear of the conveyor from a point above the press cylinders.

Figure 3 is an enlarged detail side elevation of the front or delivery end of the conveyor frame showing the parts in normal position prior to the arrival of a sheet.

Figures 4 and 5 are views of the main parts of the mechanism shown in Figure 3 showing two operative positions, Figure 4 representing the parts in their normal position when a sheet of paper has been fed to the front gauges and moved laterally into proper side registered position; while Figure 5 shows the parts in the position assumed when a sheet fails to be properly side registered and the press throw-out is operated.

Figures 6, 6^a and 7 are enlarged detail perspective views of the essential elements

of the throw-out mechanism controlled by the side register trips, Figure 6^a being a detached view looking from the right of Figures 2 and 6 showing parts to the left of gear 50.

The invention is shown in the accompanying drawings in an embodiment similar to that disclosed in the above named Patent No. 1,143,630, the press throw-out and the operating and controlling devices therefor being very similar although in the structure of said patent the control is entirely through the medium of the sheet actuated tripping devices arranged at the front gauges of the press.

Figure 1 illustrates a well known two color Miehle printing press equipped with a Dexter automatic suction feeder. It will be unnecessary to describe the details of the printing press, its operating mechanism, its throw-out mechanism, or the structure of the automatic feeder, since various types of these mechanisms are well known in the art and the specific structures form no part of the present invention. It will be sufficient to point out that the spring actuated tripping plate 1, normally held out of action by a dog 2 under the control of a vertical movable rod 3, is designed to operate through suitable mechanism for arresting the printing press and feeder and separating the impression cylinder from the form. The feeder is driven by a suitable train of auxiliary geared shafts 6, 7 from the printing press. Sheets are successively separated and fed from the automatic feeder to the conveyor belts 10, which carry the sheets from the feeder to the front gauges of the press in a well known manner.

At the front or delivery end of the conveyor frame suitable side brackets indicated at 25 rest upon the feed board 26 of the press proper and support between them suitable transverse shafts and tie rods, which carry and operate the mechanisms for acting upon the successive sheets delivered to the press gauges. These mechanisms commonly embody slow-down devices for properly presenting the sheets to the front gauges and side registering devices for positioning the sheets laterally after they have been registered at the press gauges. These usual devices for handling sheets delivered to the press will be referred to only in a general way in the relations they bear to the im-

proved sheet control of the press throw-out. Suitably journalled in one of the auxiliary side frames 25 of the conveyor frame above referred to is a cam shaft 35 carrying at its outer end a miter gear 36 meshing with a similar gear 37 secured to the end of an inclined shaft 38 extending from the gear plate of the feeder, which is driven by the shaft 7 above referred to.

10 This cam shaft 35 has keyed to it a cam
40 for actuating the throw-out operating
rock shaft 41 and a cam 45 for operating
the trip or controlling rock shaft 46, both of
which mechanisms will be hereinafter de-
15 scribed in the order mentioned. Shaft 41
is mounted in the tubular shaft 41^a which
actuates the top members of the side regis-
tering devices in a manner well understood.

The cam shaft 35 has also mounted upon it between the above named cams, a gear wheel 50 meshing with a pinion 51 keyed to one end of an auxiliary shaft 52, which extends entirely across the front end of the conveyor frame and is provided adjacent to its opposite ends with the adjustably mounted miter gears 53, which gear with and operate the side registry mechanisms of any preferred construction. These side registry mechanisms are illustrated in a general way at 55, each being mounted upon a laterally adjustable bracket including an underguide plate 56 formed in its outer edge with a notch or recess 57 for the purpose herein-after explained.

35 60 is a switch box controlling the electric motor that operates the press. This switch is under the control of a throw-out bell crank lever 65 having one arm connected to the rod 3 above referred to and another arm connected with a rod 70 connected to the upper end of a throw-out lever 71 pivoted to the machine frame at 72. Means for operating the throw-out lever 71 comprises a rod 75 pivoted to lever 71 at 76 and passing toward the 40 press through a guide yoke 77 in which is mounted a spring supported plunger 78, on which rod 75 rests and by which the rod is yieldingly held in its upper operative position. 45 Rotatably mounted in the yoke 77 above the rod 75 and member 78 is an eccentric 79 having a finger piece 80 by which it can be rotated for holding rod 75 downward- 50 ly in its lowered inoperative position when the automatic throw-out is not to be used as 55 in hand feeding.

This throw-out rod 75 carries a tappet block 85 which is adjustably mounted upon the rod by means of set screw 86. This tappet block 85 rests, when rod 75 is in its raised position, in the path of the foot 91 of a rock arm 90 keyed to the end of the throw-out operating rock shaft 41 above referred to. This rock shaft 41 carries at its opposite end adjacent to the cam 40 a rock arm 93 having antifriction roller 94 operat-

ing in peripheral engagement with the cam 40 referred to. A spring device 95 acts upon rock shaft 41 in opposition to the cam 40. When shaft 41 is rocked by cam 40 and tappet block 85 is in the path of the foot 70 91, the motor switch and press throw-out will be operated in a manner well understood.

The rod 75 carrying tappet 85 is normally supported in its elevated position in readiness for engagement by the rock arm 90 referred to on any of its periodic movements. The tappet 85 must be lowered out of the path of rock arm 90 every time a sheet passes to the press. This automatic lowering of tappet 85 is controlled by the position of the successive sheets through the mechanism which will now be described.

The controlling rock shaft 46 above referred to carries at one end a rock arm 100 to which is pivoted a link 101 having slot 85 102 engaging fixed guide pin 103 and carrying at its lower end a freely journalled grooved roller 105 which rests in engagement with the rod 75. This controlling rock shaft 46 also carries a rock arm 110 to which is pivoted a slotted strap 112 guided upon the shaft 35 and carrying antifriction roller 113 operating upon the periphery of the cam 45 above referred to. A spring rod 114 also connects with rock arm 110 and acts in opposition to the cam 45 in rocking the shaft 46. 90 95

115 represents the press gauges provided with the usual angular trips 116 adapted to be actuated by the engagement of the front 100 edge of the sheet and normally resting in the path of the notched forward ends 117^a of the feeler rods 117 adjustably mounted in the lower ends of rock arms 118 adjustably mounted upon rock shaft 46. Each time the 105 rock shaft 46 is moved the feeler rods 117 move forward slightly and in the absence of a sheet at either of the front gauges will engage one of the trips 116 to prevent the full rocking motion of rock shaft 46. If, however, the sheet is in proper registered position at the front gauges, both trips 116 will 110 be shifted so as to permit the feeler rods 117 to move past the trips to permit the complete motion of rock shaft 46. This front 115 gauge detector mechanism for controlling the press throw-out is specifically old in the art.

In addition to the control of rock shaft 46 by the front gauge detectors referred to, the present invention contemplates the use 120 (either in conjunction with said front gauge detectors or independently of them) of the controlling detectors actuated by the side registry of the sheets as will now be explained. Rock shaft 46 also has adjustably 125 mounted upon it the depending rock arms 125 formed in their lower ends with yokes 126, in each of which is mounted a pivot pin 127 extending parallel with the vertical longitudinal plane of the feed. Freely pivoted 130

upon the pin 127 is a side register detector blade or finger 130 which is free to move upon its pivot transversely of the feed, but which provides an extension of rock arm 125 which is rigid therewith longitudinally of the feed. This detector blade 130 normally rests in engagement with the notch 57 of the side register underguide plate 56 above referred to, to normally lock shaft 46 against its spring action and hold the antifriction roller 113 out of the low portion of cam 45 as indicated in Figure 3. Rock shaft 46 is provided with two of these side registry detector controls, one being employed in conjunction with each of the side registering mechanisms, it being of course understood that only one of the side controls is in use at one time, the other being shifted out of action when not in use.

The notched edge of each underguide plate 56 should be in longitudinal alignment with the side registering gauge face (not shown) with which it is employed, since the trip 130 is released from locking engagement with the notch 57 by the movement of the sheet into side registry position.

The operation of the improved mechanism will be clear with but a few words of explanation. As the successive sheets are fed from the automatic feeder to the front gauges of the press the front registry trips are actuated to move out of the path of feeler rods 117, and the action of the side register of the sheet disengages the trip 130 from the notch of the side registry underguide so that the rock shaft 46 is freed from the front and side registry controls and is permitted to rock when the low portion of cam 45 reaches roller 113. The rocking of shaft 46 lowers the tappet 85 out of the path of foot 91 of rock arm 90 when the rock shaft 41 moves, as shown in Figure 4, it being understood that the controlling cams 40 and 45 are timed to produce this succession of actions. In the event that a sheet fails to reach proper position either at the front or side registry controls, the rock shaft 46 will be held against movement with the result that tappet 85 will remain in the path of rock arm 90, as shown in Figure 5, so that the press throw-out will be operated.

I claim:

1. In a sheet feeding machine, the combination of throw-out mechanism, means controlling the operation of the same including a shaft, a front registry detecting device operated from said shaft, a side registry detecting device mounted on said shaft and projecting into the path of the sheets, and means normally holding said side registry detecting device in position to prevent rotation of said shaft, said side registry detecting device being moved into position by the sheets to permit the rotation of said shaft.
2. In a sheet feeding machine, the combination of throw-out mechanism, means controlling the operation of the same including a shaft, a front registry detecting device mounted on said shaft and projecting into the path of the sheets, and means normally holding said side registry detecting device in position to prevent rotation of said shaft, said side registry detecting device being moved into position by the sheets to permit the rotation of said shaft.

nation of throw-out mechanism, means controlling the operation of the same including a shaft, a pair of front registry detecting elements operated from said shaft, a side registry detecting element on each side of the machine mounted on said shaft and depending therefrom and projecting into the path of the sheets, means controlled by said elements preventing the rotation of said shaft when the sheet is out of registry with the front elements and one of said side elements, said front elements and one of said side elements being moved by the sheet when it is properly positioned to permit movement of said shaft.

3. In a sheet feeding machine, the combination with throw-out mechanism, of means controlling the same including a rock-shaft, a side registry detecting finger projecting from said rock-shaft into the path of sheets, and a stop with which said detecting finger normally engages to prevent movement of said rock-shaft, said detecting finger being responsive to side-registry positioning movements of sheets to be moved thereby out of engagement with said stop for permitting movement of said controlling rock-shaft.

4. In a sheet feeding machine, the combination of throw-out mechanism, means controlling the same including a shaft, a side registry detecting device mounted on and depending from said shaft into the path of the sheet, and means positioned to engage said device and prevent movement of said shaft, said device being moved by the sheet out of engagement with said means when properly positioned to permit the rotation of said shaft.

5. In a sheet feeding machine, the combination of throw-out mechanism, means controlling the same including a shaft, a side registry detecting device mounted on and depending from said shaft into the path of the sheet, and means positioned to engage said device and prevent movement of said shaft, said device being moved by the sheet out of engagement with said means when properly positioned to permit the rotation of said shaft, a front registry detecting device including a pair of pivoted elements one arranged on either side of the medial longitudinal line of the sheet, and means mounted on said shaft and engaging one or both of said pivoted elements to prevent rotation of said shaft in the event that the front edge of the sheet is not properly positioned.

6. In a sheet feeding machine, the combination of throw-out mechanism, means controlling the operation of the same including a rock shaft, two controlling rock arms projecting from said shaft, a front registry detector device, a feeler mounted on one of said rock arms and adapted to engage said device in the absence of a sheet, and a side registry detector device mounted upon the

other of said rock arms and positioned in the path of the sheet, each of said detectors being adapted to prevent the action of said rock shaft in the absence of a sheet from its 5 respective detector station.

7. The combination with a machine designed to operate upon sheets passed through it, and stop mechanism adapted to arrest the action of said machine, of operating means 10 for said stop mechanism including relatively movable coacting members by which the stop mechanism and its operating means are connected and disconnected, an intermittently acting rock shaft controlling the operative 15 relation of said members, a rock arm mounted upon said rock shaft, a side registry detecting finger pivoted upon said rock arm to move in a plane parallel with said rock shaft, and a notched sheet guiding plate in 20 the notch of which said detecting finger engages to normally lock the rock shaft against motion.

8. The combination with a machine designed to operate upon sheets passed through it, and stop mechanism adapted to arrest the action of said machine, of operating means 25 for said stop mechanism including relatively movable co-acting members by which the stop mechanism and its operating means are connected and disconnected, an intermittently acting rock shaft controlling the operative 30 relation of said members, a rock arm mounted upon said rock shaft, a side registry

detecting finger pivoted upon said rock arm to move in a plane parallel with said rock 35 shaft, a side registry device, and a notched sheet guiding plate associated with said side registry device, said detecting finger normally engaging the notch of said guiding plate to lock the rock shaft against motion. 40

9. The combination with a machine designed to operate upon sheets passed through it, and stop mechanism adapted to arrest the action of said machine, of operating 45 means for said stop mechanism including relatively movable coacting members by which the stop mechanism and its operating means are connected and disconnected, one of said members comprising a cam-operated rock shaft carrying a throw-out actuating rock arm, a second cam-operated rock shaft extending transversely of the path of sheets, a controlling rock arm fixed upon said second rock shaft and movable therewith in a vertical plane parallel with the path of 50 sheets, a side register detector finger pivotally mounted upon said controlling rock arm to move freely transversely of the path of sheets, but immovable upon said rock arm in the path of movement of sheets, and an underguide plate formed with a notch in its outer edge in which said detecting finger 55 normally engages for preventing the operation of said second rock shaft.

CARL E. CHRISTOPHEL.
